UNITED STATES PATENT OFFICE.

ALFRED ROYER, OF REED'S MILLS, OHIO.

IMPROVED DEVICE FOR HEATING ORES FOR SMELTING-FURNACES.

Specification forming part of Letters Patent No. 38,419, dated May 5, 1863.

To all whom it may concern:

Be it known that I, ALFRED ROYER, of Reed's Mills, Vinton county, Ohio, have invented a new and useful Improvement in Devices for Preheating Ore; and I do hereby declare the following to be a full, clear, and exact description thereof, reference being had to the annexed drawings, making part of this specification.

Devices heretofore essayed for roasting and preheating ore by the waste heat of the melting-furnace have proved impracticable, in consequence of the baskets or other receptacles becoming melted by the intense heat; and they have, also, during the brief period of their operation, proved only partially effective, by reason of the unequal contact of the flames with the ore. To remedy these defects, I have provided a peculiar grate, adapted to withstand the intense heat for an indefinite period, and to present the ore uniformly in contact with the heated effluvia of the tunnel-head.

Figure 1 is a longitudinal section of my improvement. Fig. 2 is a transverse section thereof.

A represents the tunnel-head of a smelting-furnace.

B B' is the flue, surmounted by a pair of cylindrical boilers, CC', for operating the blast, *et cetera*.

My arrangements for preheating the ore consists as follows.

D is a swinging grate whose end bars, d, and cross-bars d' consist of hollow tubes for holding water. The arrangement of this grate is such that in its upper position (see Fig. 1) it is adapted to receive and hold the ore in an extended form, so as to intercept the hottest portion of the flame, while in its depressed position (see Fig. 2) it is adapted to discharge the heated ore into the furnace.

E E' are hollow trunnions, by which the grate is hinged to the flue sides, and through which it is charged with water.

F is a cold-water tank having a pipe, G, which conducts water into the grate D. Partitions (see dotted lines H) compel the water to meander through the entire series of bars until it issues through the trunnion E' into a pipe, I, which may convey it back to the tank F, or to a feed-tank for the boilers, or may discharge it. A forced circulation of water

may be secured by a "Giffard's injector," J, or by a force-pump, or a hydrostatic column.

In order to enable the elevation and depression of the grate without disconnecting the water-supply, the pipes G and I are connected to the trunnions by flexible joints K K'.

L is a counter-balance, which slightly outweighs the unloaded grate, so as to return it automatically to its upper position when relieved of its load of ore.

M is a self-acting catch, which retains the grate to its upper position on its return from unloading.

F is a hopper through which the ore is fed onto the grate. The ore may be dumped or discharged into the hopper N from an ordinary corf or truck run out upon an elevated tramway.

O is a hopper by which the coal and flux are fed to the tunnel-head.

P is a chute to carry into the tunnel-head whatever fragments of ore drop through the grate.

For a customary furnace, I have adopted the following proportions: I make the grate six and one-half feet long and four and one-half feet wide. The end bars are two and one-half inches square. The cross-bars are two and one-half inches wide on top, one and one-half inch wide at bottom, and two inches deep. In some cases, however, a somewhat greater depth than the above may be found advisable. The intervals between the cross-bars are one inch, the object being to have them as wide as possible, so as to afford, as far as practicable, an unobstructed passage of the flame through every part of the charge of ore. The ore, broken to about egg size, is deposited upon the grate in quantities of from nine hundred to twelve hundred pounds, and having remained on the grate from twenty-five to thirty minutes, becomes red-hot and throws off most of its sulphur, phosphorus, and other volatile impurities. The charge of coal and limestone being then thrown in, the catch M is withdrawn and the grate, now descending, discharges its load of heated ore into the tunnel-head, when, being overbalanced by the weight L, it returns automatically to its upper position for another charge.

The form selected to illustrate my invention is not necessarily the only one that may be

employed, as various modifications will readily suggest themselves. For example, gudgeons may extend from the free end or bar of the grate through slots in the boiler-furnace concentric with the trunnions, and, rods being attached thereto, the grate may be elevated by a lever, thus dispensing with a counter-balance; or two self-acting catches may engage said gudgeons and be simultaneously released by operating a single lever connected with both. I claim herein as new and of my invention— The grate D, adapted to present the ore in

an open condition to the flame of the tunnel-head and to discharge the heated ore, the said grate being preserved from destruction by a current of water traversing its interior, the whole being combined and operated substantially as set forth.

In testimony of which invention I hereunto set my hand,

ALFRED ROYER.
